SHOE FORM

Alfred G. Legge, Brockton, Mass.

Application March 14, 1933. Serial No. 660,653

2 Claims. (Cl. 12—128.4)

This invention relates to hollow shoe forms having a thin flexible wall adapted to be spread into engagement with the upper of a shoe. It is an object of the present invention to provide

5 improved means for maintaining the walls of the toe part of the form in engagement with the toe part of the upper of the shoe.

The invention will be more clearly understood from the following description in conjunction 10 with the accompanying drawings: in which,

Fig. 1 is a plan view, partly broken away, of a shoe form embodying the invention;

Figs. 2 and 3 are sectional views taken upon the lines 2—2 and 3—3 of Fig. 1, respectively;

15 Fig. 4 is a view similar to Fig. 3 showing the form collapsed;

Fig. 5 is a plan view, partly broken away, of a shoe form inserted in a lady's shoe; and

Fig. 6 is a sectional view taken on the line 6—6 20 of Fig. 5.

Before explaining in detail the present invention it is to be understood that the invention is not limited in its application to the details of construction and arrangement of parts illustrated 25 in the accompanying drawings, since the invention is capable of other embodiments and of being practiced or carried out in various ways. Also it is to be understood that the phraseology or terminology employed herein is for the purpose 30 of description and not in limitation, and it is not intended to limit the invention claimed herein beyond the requirements of the prior art.

In the accompanying drawings a shoe form F is shown comprising a hollow toe part 10 of sheet celluloid or other flexible sheet material, the opposite side walls of which are provided with bottom inturned flanges 11 and 12 normally positioned in a common plane. The flange 11 is provided with a pair of recesses forming raised 35 portions 13 and 14 therein and the flange 12 is provided with a recess forming a raised portion 15 therein. Arms 16 and 17 are secured, as by rivets 18, to the raised portions 13 and 15 in the flanges 11 and 12 respectively. The free ends 40 of the arms 16 and 17 are formed with eyes 20 and 21 surrounding and pivotally engaging a hollow bearing 22 which serves to pivotally connect the arms 16 and 17 so that they may swing in a plane intersecting the general plane of the in- 45 turned flanges 11 and 12. An arm 25 is secured at one end, as by a rivet 26, to the raised portion 14 in the flange 11. The arm 25 extends inwardly and then rearwardly through the hollow bearing 22 and is provided at its free end with a down- 50 wardly extending prong 27 adapted to engage the

insole 28 of a shoe 29. The arm 25 is also provided with an upwardly extending intermediate portion 30 which is adapted to engage the bearing 22.

When the shoe form of the invention is to be 60 inserted in a shoe, the arms 16 and 17 are swung upwardly, as shown in Fig. 4, thereby moving the opposite side walls of the form relatively toward one another to collapse the form and at the same time moving the arm 25 upwardly to bring the downwardly extending prong 27 above the general plane of the inturned flanges 11 and 12. The form in this condition is inserted within the toe part of the shoe and the arms 16 and 17 are 65 swung downwardly past their dead center position and in engagement with the insole of the shoe, as shown in Figs. 2 and 3. This causes the side walls of the form to be moved relatively 70 away from one another to expand the form in engagement with the upper of the shoe and at the same time causes the downwardly extending prong 75 to be brought into engagement with the insole of the shoe. Any tendency for the form to be forced rearwardly in the shoe is resisted by the engagement of the prong 27 with the insole 80 of the shoe and by the upwardly extending intermediate portion 30 of the arms 25 engaging the bearing 22.

In forms for certain types of shoes, such as ladies' shoes, the arm 25 may be eliminated, if 85 desired, and the side walls of the form shaped to engage the portion of the shoe where the upper merges with the shank. This is illustrated in Figs. 5 and 6 wherein a form F' is shown inserted in a lady's shoe 29'. The form F' comprises a 90 hollow toe part 10' of sheet celluloid or other flexible sheet material, the side walls of which are provided with bottom inturned flanges 11' and 12', normally positioned in a common plane. The rear ends of the side portions of the form are so 95 shaped and merged with the rear ends of the inturned flanges 11' and 12' as to snugly engage the portion S of the shoe 29' where the upper merges with the shank of the shoe so as to prevent 100 the form F' being forced rearwardly in the shoe. The flanges 11' and 12' are provided with recesses forming raised portions 13' and 15'. Arms 16' and 17' are secured, as by rivets 18', to the raised 105 portions 13' and 15' respectively. The free ends of the arms 16' and 17' are formed with eyes 20' and 21' surrounding and pivotally engaging a hollow bearing 22' which serves to pivotally connect the arms 16' and 17' so that they may swing 110 in a plane intersecting the common plane in which

the inturned flanges 11' and 12' are normally positioned.

I claim:

- 5 1. A shoe form comprising a hollow flexible toe part having its opposite side walls provided with bottom inturned flanges, and an arm secured to each of said flanges above the general plane thereof, said arms being pivotally connected to swing in a plane intersecting the plane of said flanges to move said side walls relatively to expand and collapse said form whereby said arms may be swung to and maintained in a slightly off center position in engagement with the insole of a shoe to maintain said form expanded in said shoe.
- 10 2. A shoe form comprising a hollow flexible toe part having its opposite side walls provided with

bottom inturned flanges, an arm secured to each of said flanges above the general plane thereof, a hollow bearing to which said arms are pivotally connected to swing in a plane intersecting the plane of said flanges to move said side walls relatively to expand and collapse said form whereby said arms may be swung to and maintained in a slightly off center position in engagement with the insole of a shoe to maintain said form expanded in said shoe, and a member extending through said bearing having a downwardly extending prong adapted to engage the insole of a shoe and having an intermediate upwardly extending portion adapted to engage said bearing to prevent rearward movement of the form. 80 85 90
